UNITED STATES PATENT OFFICE.

RUFUS C. CRAWFORD, OF MCKEESPORT, PENNSYLVANIA, ASSIGNOR OF ONE-HALF TO
JOHN T. MOYER, OF OAKMONT, PENNSYLVANIA.

EXPLOSIVE DEVICE.

1,243,817.

Specification of Letters Patent. Patented Oct. 23, 1917.

Application filed October 18, 1915. Serial No. 55,612.

To all whom it may concern:

Be it known that I, RUFUS C. CRAWFORD, a citizen of the United States, and a resident of McKeesport, in the county of Allegheny 5 and State of Pennsylvania, have invented a new and useful Improvement in Explosive Devices; and I do hereby declare the following to be a full, clear, and exact description thereof.

10 My invention pertains to explosive devices for use in warfare, and relates particularly to torpedoes. It is an object of my invention to produce a torpedo in which much of the complicated machinery now ordinarily employed will be done away with. It is another object of my invention to produce a torpedo which will be relatively cheap to produce, and which will be capable 15 of traveling at a high speed in a straight line. It is another object of my invention to provide a torpedo with a simple and safe means for preventing the possibility of explosion of its high explosive charge, except after the torpedo has been launched. It is 20 another object of my invention to provide a torpedo with means for causing its explosion at the end of its travel, regardless of whether it does or does not hit the object aimed at. And other and further objects of my invention will appear from the 25 following specification taken in connection with the appended claims.

I have described, by way of example, in the following specification, and shown in 30 the accompanying drawings, one form of explosive device constructed in accordance with my invention. It is to be understood, however, that my invention may be embodied in other forms, and that changes may 35 be made in the constructional features of the device described and shown, without exceeding the scope of the invention, as defined in the appended claims.

In the drawings:

40 Figure 1 is a longitudinal section taken through a torpedo constructed in accordance with my invention, the section being taken as on the line 1—1 of Fig. 4;

45 Fig. 2 is an end view of the same on an enlarged scale;

Fig. 3 is an enlarged detail showing the manner of mounting the directing vanes;

50 Fig. 4 is an enlarged section taken on the line 4—4 of Fig. 1, looking in the direction 55 of the arrows, the arming ring being shown

in full lines in its unarmed position, and in dotted lines in its armed position;

Fig. 5 is a section taken on the line 5—5 of Fig. 4, looking in the direction of the arrows; 60

Fig. 6 is an outside view of part of the head portion of the torpedo, showing the inspection opening and the means for setting the arming ring;

Fig. 7 is a section taken on the line 7—7 65 of Fig. 1, looking in the direction of the arrows; and,

Fig. 8 is a section on the line 8—8 of Fig. 7, looking in the direction of the arrows.

Like reference characters refer to like 70 parts throughout the following specification and the several figures of the accompanying drawings.

Referring now particularly to Figs. 1—3, the construction of the torpedo shown in the 75 drawings includes a head 10 which is screwed onto a central threaded boss 11 of a cylinder 12, the exterior surface of the latter forming a continuation of the head 10. The cylinder 12 is open at its rear end, 80 to receive the front part of a second cylinder 13, the latter having a front wall 14 which separates the cylinders from each other. Located centrally in the rear part of the cylinder 13, is a tube 15, which terminates at its front end in a flange 16 which fits closely within the cylinder 13, thereby forming a chamber 17, at the front part of the cylinder 13. The rear end of the cylinder 13 is closed by an end plate 18, which 85 has an opening therein for receiving the open end of the tube 15.

The torpedo described herein is primarily intended to be fired from a mortar through the air into the water, completing its travel 90 in the latter. To this end, the chamber 17 and the tube 15 are filled with combustible material, such as a relatively slow burning explosive for instance, gunpowder. The firing of the mortar will ignite the powder 95 in the tube 15. The burning of the powder in the tube 15 and chamber 17 will result in a strong stream of the gases of combustion issuing from the rear end of the tube 15, such stream continuing to issue until the 100 powder in the chamber 17 is exhausted. The stream of gas issuing from the tube 15 will propel the torpedo rapidly through the air and water. In order to aid in maintaining 105 the torpedo in a straight line, and there- 110

by assist in obtaining accuracy of marksmanship, the torpedo is provided, at its rear end, with directing vanes 19. These vanes are shown as being four in number; and each 5 is provided with a pair of tubular stems 20, which fit over pins 21 mounted in the tube 15. Coil springs 22 surround the stems 20, and tend to press the vanes 19 outward. The cylinder 13 is provided with slots for 10 receiving the vanes 19, the vanes being a width such that they may be pushed in, against the action of the springs 22, until their outer edges are flush with the cylinder 13 (Fig. 1, full lines). When the torpedo is 15 to be launched, the vanes 19 are all pushed in; and the torpedo, in that condition, is inserted into the mortar, the vanes being thereby held in place. As soon as the torpedo leaves the mortar the vanes 19 spring 20 out into the operative position indicated in dotted lines in Fig. 1.

Referring now to Figs. 1, 4 and 5, the head 10 is provided with a central cylindrical chamber 23, in which is slidably mounted a 25 cylindrical block 24 having a central firing pin 25. The block 24 is normally held against movement by a latch, to be herein-after described; but, when it is not so held, it will travel forward in the chamber 23 as 30 soon as the torpedo is suddenly checked by striking an object. When the block thus travels forward, it strikes a detonating cap or the like 26. The cap 26, when fired, ignites a charge contained in a pair of restricted passages 27 which terminate in bores 28 formed in the head 10 and extending toward the rear of the same. The cylinder 12, which is filled with a high explosive, such as guncotton or the like, is provided with two 35 tubes 29, which are disposed so as to form continuations of the bores 28. In the bores 28 there are provided miniature projectiles 30, which are in the form of cartridges filled with fulminate or the like and having priming caps 30^a at their front ends. When the cap 26 ignites the charge in the passages 27 and bores 28, the miniature projectiles 30 are shot forward into the tubes 29, where 40 their priming caps 30^a impact against pins 31, thereby causing the explosion of the fulminate. This explosion of the projectiles shatters the tubes 29, and effects the explosion of the high explosive charge in the cylinder 12.

55 In order to prevent the charge in the cylinder 12 from being exploded accidentally, an arming ring 32 is provided (Figs. 1, 4 and 5). The ring 32 is rotatably mounted in an annular groove formed in the rear face 60 of the head 10, and is provided with holes 33 of the corresponding size to the bores 28. It will be seen that the miniature projectiles 30 can only be fired into the tubes 29 when the ring 32 is in such position that these holes 65 33 are placed opposite the ends of the bores

28. The ring 32 is normally held out of this position, that is, is held in a position in which the holes 33 are not placed opposite the bores 28, by a rod 34 which extends lengthwise of the torpedo and enters a small 70 hole in the ring.

Mounted on a pin 35, carried by the head 10, is a rod 36, on which is mounted a coil spring 37, such rod and spring being located in a recess 38, formed in the ring 32, with the spring 37 engaging against one end wall of the slot. The ring 32 is provided with an inclined slot 39, which receives the bent over end 40 of a latch pin 41 which is radially movable in the head 10, and the end of 80 which engages in an annular groove 42 formed in the firing block 24. It will be seen that when the rod 34 is withdrawn from its hole in the ring 32, the spring 37 will cause the ring 32 to rotate into the position 85 indicated in dotted lines in Fig. 4. In this position, the holes 33 are in alignment with the bores 28. Also, by the rotation of the ring, the pin 41 will be withdrawn from the slot 42, thereby releasing the firing block. 90

In order to effect the withdrawal of the rod 34 to release the ring 32, such rod is mounted in a tube 43 (Figs. 7 and 8) which terminates in a chamber 44 formed in the end-plate 18. This chamber contains an explosive charge, and communicates, by a restricted passage 45, with the rear end of the tube 15. At the rear end of the chamber 44, the rod 34 is provided with a head 46. It will be seen that, as soon as the 100 powder in the tube 15 is fired upon the torpedo being launched, the charge in the passage 45 and the chamber 44 will be ignited, causing the head 46 to be driven out from the chamber 44, and the rod 34 consequently to be pulled out from its hole in the ring 32, thereby releasing the ring 32 and arming the torpedo.

The head 10 is formed with a longitudinal passage 47 (Figs. 7 and 8), which communicates with one of the firing passages 27 referred to above. This passage communicates with the chamber 17 through a tube 48 forming a continuation of the passage, both the tube and the passage carrying an explosive charge. The result is that, when the powder in the chamber 17 is nearly burnt out, it will fire the charge in the tube 48 and passages 47 and 27, thereby causing the explosion of the contents of the cylinder 12. 110 Normally, the ring 32 forms a barrier between the tube 48 and the passage 47; but, when the ring 32 is in its armed position, a hole 49 therein brings the tube and the passages 47 and 27 into communication. 115

The head 10 is formed with an opening 50 which discloses a portion of the edge of the ring 32, such opening being closed by a removable transparent cover 51. At this point, the edge of the ring 32 is formed with 120

a hole 52 for receiving a pin or the like, by means of which the ring 32 may be rotated. The position of the hole 52, as seen through the transparent cover 51, will thus always indicate whether the ring 32 is in its armed or in its unarmed position. When it is desirable to set the ring 32, this can be done by removing the cover 51, pulling the ring around to the position shown in the full lines 10 in Fig. 4, and then inserting the rod 34 into its hole in the ring 32, the charge having first been placed behind the head 40 of the rod 34.

The operation of the form of torpedo 15 shown and described is as follows:

Prior to insertion in the mortar, the ring 32 is in the position shown in full lines in Fig. 4, in which condition the firing block 24 is locked against movement, the tubes 29 20 are cut off from the bores 28 and the passage 47 is cut off from the tube 48. The torpedo is thus unarmed; and, in that condition, is inserted in the mortar, the directing vanes 19 being first pressed in. When 25 the mortar is fired, the torpedo is driven out therefrom, and at the same time the charge in the tube 15 is ignited, causing a stream of gas to issue from the tube 15 and thereby propel the torpedo, the vanes 19 springing 30 out into their operative position. As soon as the charge in the tube 15 has been fired, the charge in the passage 45 and chamber 44 will be exploded, causing the rod 34 to be withdrawn from the ring 32, and thereby 35 permitting the ring to snap over into position shown in dotted lines, in Fig. 4. In this position the tubes 29 are in communication with the bores 28, the firing block 24 is freed, and the tube 48 is in communication 40 with the passage 47, the torpedo being thus completely armed. When the torpedo strikes the object aimed at, the shock will cause the firing block 24 to snap forward in the chamber 23, whereby its pin 45 25 will detonate the cap 26, and cause the miniature projectiles 30 to be fired against the pins 31, thereby exploding the high explosive charge in the cylinder 12. Should the torpedo fail to strike the object aimed at, 50 the powder in the chamber 17 will, when nearly exhausted, ignite the charge in the tube 48 and passage 47, thereby exploding the charge in the cylinder 12 just about when the torpedo has come to the end of its 55 travel. It may be that the torpedo will, at this time, be near enough to the object aimed at, to do damage; and in any case, the source of danger created by an armed torpedo floating at will on the water is removed.

60 It will be seen that the torpedo described above is relatively simple in construction and cheap of manufacture. The use of complicated propelling machinery is done away with; and there is practically nothing to get 65 out of order. The torpedo is very safe for

storage and for handling prior to firing; and an added advantage is that it explodes on the completion of its journey, and thus does not become a floating danger to vessels of all kinds.

In describing the form of torpedo shown herein, it has been referred to as being fired from a mortar or the like. It may, however, be simply dropped from a height onto the object aimed at. In this case, there is present the additional advantage that the issuing gases cause the torpedo to travel downward much faster than it would if merely impelled by gravity, so that aim is rendered more accurate, and the deflecting effect of air currents is considerably lessened. When the torpedo is to be used in this way, and in other ways which would entail the torpedo striking the water with great force, it may be necessary to modify the firing mechanism in such a way as to prevent its actuation upon the impact of the torpedo with the water, but permit such actuation when the torpedo strikes the object aimed at. This and other changes in the embodiment which I have chosen as illustrating my invention, are within the scope of such invention, what I claim being:

1. An explosive device comprising a body carrying an explosive charge, and having a chamber therein for receiving combustible material, said chamber having a rearwardly directed opening for permitting egress of the gases of combustion, means for effecting the explosion of said charge, and means for rendering said exploding means inoperative, said last-named means being releasable by the ignition of said combustible material.

2. An explosive device comprising a body carrying an explosive charge, and having a chamber therein for receiving combustible material, said chamber having a rearwardly directed opening for permitting egress of the gases of combustion, means for exploding said charge, a movable member for normally maintaining said exploding means in an inoperative condition, and an explosive charge connecting with said chamber for moving said member when said combustible material is ignited.

3. An explosive device comprising a body carrying an explosive charge, and having a chamber therein for receiving combustible material, said chamber having a rearwardly directed opening for permitting egress of the gases of combustion, means for effecting the explosion of said charge, a longitudinally movable member normally preventing the operation of said exploding means, said body being provided with a chamber for receiving a portion of said member and connecting with said first-named chamber, and an explosive charge in said second-named chamber, whereby said member is moved when said second-named charge is ignited.

4. An explosive device comprising a body carrying an explosive charge and having a chamber therein for receiving a combustible material, a rearwardly opening tube connecting with said chamber, means for effecting the explosion of said charge, and a movable member normally preventing the operation of said exploding means, said body being formed with a charge-containing chamber 10 surrounding a part of said member, said last-named chamber communicating with said tube. 5. An explosive device comprising a body having a chamber therein for receiving combustible material, said chamber having a rearwardly directed opening for permitting egress of the gases of combustion, an explosive charge contained in said body, a second charge adapted when ignited to effect the explosion of said first named charge, impact-operated means for effecting the ignition of said second named charge, and ignition means between said chamber and said second-named charge disposed so as to effect the ignition of said second-named charge substantially when the burning of said combustible material is completed. 6. An explosive device comprising a body having a chamber therein for receiving combustible material, said chamber having a rearwardly extending opening for permitting egress of the gases of combustion, an explosive charge contained in said body, means for effecting the explosion of said charge substantially when the burning of said combustible material is completed, and automatically releasable means for normally preventing the operation of said last-named means. 7. In an explosive device, a body having a chamber therein for receiving an explosive charge, a head, impact-operated means carried by said head for exploding said charge, releasable means for normally preventing communication between said head and said body and automatic mechanism for operating said releasable means, said means being adapted to be released at a predetermined time by a supplemental explosive charge in said body portion. 8. In an explosive device, a body having a chamber therein for receiving an explosive charge, a head, impact-operated means carried by said head for exploding said charge, releasable means for normally preventing communication between said head and said body, and a supplemental explosive charge in said body portion for automatically releasing said last-named means when said device is launched. 9. In an explosive device, a body having therein a chamber for receiving an explosive charge, and having a bore for receiving a movable explosive member, said member being adapted to be exploded by a supplemental charge after said device has reached its object, releasable means for preventing communication between said bore and chamber and automatic mechanism for operating said releasable means, said last-named means being released by a second supplemental explosive charge. 10. An explosive device comprising a body having a chamber therein for receiving an explosive charge and having a bore therefor for receiving a movable explosive member, means contained in said chamber and disposed in alignment with said bore, for effecting the explosion of said member, releasable means for normally preventing communication between said bore and chamber, and explosive means for releasing said last-named means upon said device being launched. 11. An explosive device comprising a body having a chamber therein for receiving an explosive charge, a second chamber for the reception of a combustible charge, said first-named chamber having a bore containing a movable explosive member, an explosive charge for causing movement of said member, impact-operated means for igniting said last-named charge, and means automatically releasable when the device is launched for normally preventing the operation of said last-named means, said releasable means being operated by a supplemental charge adapted to be exploded by said combustible material. 12. An explosive device comprising a body having a chamber therein for receiving an explosive charge, and having a bore for receiving a movable explosive member, an explosive charge for causing movement of said member, impact-operated means for igniting said last-named charge, releasable means for normally preventing the operation of said last-named means, and explosive means for releasing said prevention means upon the device being launched. 13. An explosive device comprising a body having a chamber therein for receiving an explosive charge and having a bore for receiving a movable explosive member, a charge for causing movement of said member, impact-operated means for igniting said last-named charge, releasable means for normally preventing the operation of said last-named charge, means contained in said chamber and disposed in alignment with said bore, for causing the explosion of said member, and releasable means for normally preventing communication between said bore and said chamber, said means being adapted to be operated by a supplemental explosive charge at a predetermined time. 14. An explosive device comprising a body having a chamber therein for receiving an explosive charge and having a bore for receiving a movable explosive member, a

charge for causing movement of said member, impact-operated means for igniting said last-named charge, releasable means for normally preventing the operation of said 5 igniting means, means contained in said chamber and disposed in alinement with said bore, for causing the explosion of said member, releasable means for normally preventing communication between said bore 10 and said chamber, and a supplemental explosive charge for releasing said first and second-named prevention means upon the launching of the device.

15. An explosive device comprising a body carrying an explosive charge, and having a chamber therein for receiving combustible material, said chamber having a rearwardly directed opening for permitting egress of the gases of combustion, means for 20 effecting the explosion of said charge, a locking member normally preventing the operation of said exploding means, said body being provided with a chamber for receiving a portion of said member and connecting 25 with the first-named chamber, and an explosive charge in said second-named chamber, whereby said member is moved at a predetermined time.

16. An explosive device comprising a body having a chamber therein for receiving combustible material, said chamber having a rearwardly-extending opening for permit-

ting egress of the gases of combustion, an explosive charge contained in said body, means for effecting the explosion of said 35 charge, and releasable means for normally preventing the operation of said last-named means, said releasable means being operated by an explosive charge.

17. An explosive device comprising a 40 body carrying an explosive charge and having a chamber therein for receiving combustible material, a rearwardly-opening tube connected with said chamber, said body having a bore for receiving an explosive 45 member, a charge for causing movement of said member, impact operated means for igniting said last-named charge, releasable means for normally preventing the operation of said igniting means, means contained in said chamber and disposed in alinement with said bore for causing the explosion of said member, releasable means for normally preventing communication between said bore and said chamber, and a 50 supplemental explosive charge for releasing said first and second-named preventing means.

In testimony whereof I, the said RUFUS C. CRAWFORD, have hereunto set my hand.

RUFUS C. CRAWFORD.
